CLAIM

The ornamental design for an combined laundry hamper frame and hanger therefor, as shown and described.

DESCRIPTION

FIG. 1 is a perspective view of a combined laundry hamper frame and hanger therefor showing a new design shown mounted over a door;

FIG. 2 is a side elevational view thereof, the opposite side being a mirror image, shown with the oval frame in an alternate position; and,

FIG. 3 is a perspective view of a second embodiment of the design shown in FIGS. 1 and 2, the only difference residing in the appearance of a mounting hook.

The broken lines showing of a laundry bag, door, and closet bar are for illustrative purposes only and form no part of the claimed design.
